UNITED STATES PATENT OFFICE.

FRANCIS P. KENNEY AND WILLIAM J. ELLIOTT, OF PHILADELPHIA, PENNSYLVANIA.

RIVETING-MACHINE.

1,236,785.

Specification of Letters Patent. Patented Sept. 4, 1917.

Application filed June 27, 1916. Serial No. 106,113.

To all whom it may concern:

Be it known that we, FRANCIS P. KENNEY and WILLIAM J. ELLIOTT, of Philadelphia, in the county of Philadelphia and State of Pennsylvania, have invented certain new and useful Improvements in Riveting-Machines, whereof the following is a specification, reference being had to the accompanying drawings.

10 The invention relates to riveting machines and more particularly to that type of riveting machine adapted to be used in connection with heavy plates, such as are used in boilers and the like, and also for bridge and 15 structural work.

In machines of this type, the work which is being riveted is suspended between the riveting dies and has a tendency to swing, and drift out of line, or ahead and away 20 from the plunger die, due to the momentum caused by the thrust of the plunger die and the sudden retarding in velocity caused by the rivet encountering the stationary die.

An object of the invention is to provide 25 means for holding the work in operative position so as to prevent it from swinging or drifting out of line.

Another object is to provide a cushioning means, whereby the work is properly spaced 30 from the stationary die and the shock of the encounter minimized, so as to prevent the possibility of the rivet being canted or pushed out in back.

Still another object is to provide means 35 for alining the work so that the rivet is always brought in position directly between the two dies.

With these and other objects in view, we provide cushioning means, such as plungers, 40 in connection with both the movable and stationary dies. These plungers project forward in advance of both dies and engage and steady the work so as to prevent it from swinging when the dies engage the rivet. 45 We further provide that the heads of the plungers are so shaped and spaced as to engage the heads of the rivets on either side of the one being upset, so as to hold the rivet in exact alinement between the dies.

50 Referring to the drawings, Figure I, is a diagrammatic plan view showing a portion of a riveting machine and the adaptation of our invention thereto.

Fig. II, is a similar view illustrating the 55 machine in riveting position.

Fig. III, is a view of the same, partly in elevation and partly in section.

A machine constructed according to our invention comprises generally jaws 1, 1, which terminate in head 2, which carries 60 stationary die 3, and head 4, which houses the movable or plunger die 5.

Mounted on head 2, on either side of die 3, are cushioning plungers 8, and 9. These plungers work in cylinders 10, and 11, and 65 are provided with adjustable heads 12, and 13, appropriately recessed at 14, and 15, to engage rivet heads 62, and 63. By engaging the rivet heads the plungers serve not only to center the work 16, but also to prop- 70 erly space it, from stationary die 3, so that it is at the proper distance when rivet blank 17, which is to be upset is first engaged by movable die 5. This spacing distance may be adjusted by means of bolt and screw con- 75 nections 19, see Fig. III.

Similarly mounted on head 4, and on either side of movable die 5, are advancing plungers 20, and 21. These plungers work in cylinders 22, and 23, and are provided 80 with adjustable socket heads 24, and 25, ap- propriately recessed at 26, and 27, and adapted to engage rivet heads 60, and 61, on the opposite ends of rivet heads 62, and 63, engaged by adjustable socket heads 14, 85 15 and 15.

Plungers 20, and 21, may be operated by any appropriate pneumatic or hydraulic means which may conveniently be drawn from the same source as that used to operate 90 movable die 5. In the embodiment shown in the drawings, the fluid enters through inlet pipe 30, controlled by valve 31. When the valve is in the position shown in Fig. I, fluid is admitted through pipes 32, and 33, 95 to the forward ends of cylinders 22, and 23, and the plungers are moved to their back- ward position as shown. In this position valve 31, also connects pipes 34, and 35, with outlet pipe 36, so that any fluid which may 100 have been in the rear ends of cylinders 22, and 23, is thereby allowed to escape. When, however, valve 31, is turned to the position shown in Fig. II, pipes 34, and 35, are con- 105 nected with inlet pipe 30, and the plungers moved forward. At the same time pipes 32, and 33, are connected with outlet pipe 36, so that the fluid in the forward ends of the cylinders is permitted to escape.

Plungers 20, and 21, are so adjusted in 110

relation to movable die 5, that when pressure is admitted they move forward together with the plungers in advance of the die, as shown in the drawings. In this way the 5 first contact with the work is made by adjustable socket heads 24, and 25, which engage rivet heads 60, and 61, on either side of rivet blank 17. In order that the socket heads may be in a proper position to engage 10 these rivet heads, they may be laterally adjusted by means of bolt and screw connections 40, and 41, by which the distance between cylinders 22, and 23, may be varied. So also the angle at which the socket heads 15 are set, may be adjusted by means of crowned connections 42, and 43, best shown in Fig. III. After sockets 24, and 25, have engaged their respective rivet heads plungers 20, and 21, move the whole work toward stationary die 3, until rivet heads 62, 20 and 63, on the other side are engaged by socket heads 12, and 13. These heads are also adjustable by means of similar crowned connections 44, and 45, and capable of lateral regulation by means of screw bolt connections 46, and 47. In this position the engagement of the rivet heads by the socket heads holds the work firmly so as to be incapable of any swinging or drifting motion. 25

30 The work is, however, only held under a yielding pressure, by each of the plungers 8 and 9. These plungers are identical and a description of one will, therefore, suffice for both. Plunger 9, is formed with a head 35 50, adapted to slide in cylinder 11, under the action of a spring 51, which abuts against head 52. Head 52, is controlled by set screw 53, and by means of it the tension of the spring may be regulated. The tension of 40 the springs, however, is not sufficient to affect the action of movable die 5, when it moves forward and upsets rivet 17; consequently, it carries the whole work with it until the parts are in the position shown in 45 Fig. II.

In operation the work is suspended between jaws 1, 1, and the rivet blank to be upset put in place. The distance between plungers is regulated and the socket heads 50 set at the proper angle to engage the adjacent rivet heads. If no rivets have been driven before, dummy rivet heads are placed in the holes so that the work may be properly engaged and centered. Valve 31, is 55 turned as shown in Fig. II, so that plungers 20, and 21, move forward and together with plungers 8, and 9, engage the work, so that rivet blank 17, is accurately centered and the work is properly spaced from stationary 60 die 3, when the rivet blank receives the impact from movable die 5.

The effect of cushioning plungers 8, and 9, is to hold the work in such a position that practically no further motion of the work 65 takes place and both heads are formed prac-

tically simultaneously at the first moment of contact of movable die 5, with rivet blank 17. What little movement there is, due to the flattening of the ends of rivet blank 17, is taken up by cushioning springs 51, which 70 yield to the impact of movable die 5, upon the work. At the same time advancing plungers 20, and 21, being under pressure, move forward correspondingly, so that the work is always held and kept in its proper 75 relative position.

Having thus described our invention, we claim:

1. In a riveting machine, the combination of a movable die and a stationary die; means 80 connected with both of said dies adapted to coöperate to engage the work, whereby the work is properly centered in relation to said dies.

2. In a riveting machine, the combination 85 of a movable die and a stationary die, means coöoperating with said stationary die for spacing the work therefrom, and means co-operating with both of said dies for centering the work between the stationary and 90 movable dies.

3. In a riveting machine, the combination of a movable die and a stationary die, means coöoperating with said dies adapted to engage rivet heads in the work whereby the 95 work is properly centered between the stationary and movable dies.

4. In a riveting machine, the combination of a stationary die and a movable die, a plunger mounted adjacent said stationary 100 die adapted to engage a rivet head in the work to be riveted, whereby the work is properly centered and spaced from said stationary die.

5. In a riveting machine, the combination 105 of a stationary die and a movable die, a plunger mounted adjacent said stationary die adapted to engage a rivet head in the work to be riveted, whereby the work is properly spaced from said stationary die, 110 and means for cushioning said plunger.

6. In a riveting machine, the combination of a stationary die and a movable die, a plunger mounted adjacent said stationary 115 die, a socket head, mounted on said plunger, said socket head being recessed to engage a rivet head on the work being riveted.

7. In a riveting machine, the combination of a stationary die and a movable die, a plunger mounted adjacent said stationary 120 die, a socket head mounted on said plunger and recessed to engage a rivet head on the work being riveted, and means for adjusting said socket head.

8. In a riveting machine, the combination 125 of a stationary die and a movable die, a plunger mounted adjacent said stationary die, said plunger being adapted to slide in a cylinder under the tension of a spring, and to engage a rivet head in the work be- 130

ing riveted, whereby the work is properly centered and spaced from said stationary die.

9. In a riveting machine, the combination 5 of a stationary die and a movable die, a plunger mounted adjacent said stationary die, said plunger being adapted to slide in a cylinder, and means for adjusting said cylinder in relation to said stationary die.
10. In a riveting machine, the combination 10 of a stationary die and a movable die, plungers mounted on either side of said stationary die adapted to engage rivet heads in the work being riveted, and means for 15 adjusting the distance between said plungers.

11. In a riveting machine, the combination 20 of a stationary die, and a movable die, plungers mounted adjacent said movable die, adapted to engage rivet heads in the work being riveted, whereby the work is properly aligned between said dies.

12. In a riveting machine, the combination 25 of a stationary die, and a movable die, a plunger mounted adjacent said movable die, a socket head mounted on said plunger, said socket head being recessed to engage a rivet head.

13. In a riveting machine, the combination 30 of a stationary die, and a movable die, a plunger mounted adjacent said movable die, a socket head mounted on said plunger and recessed to engage a rivet head, and means for adjusting said socket head.

35 14. In a riveting machine, the combination of a stationary die and a movable die; a cylinder mounted adjacent to said movable die; a plunger adapted to slide in said cylinder and pneumatic connections whereby said plunger is moved forward in advance of said die, so as to engage the work and properly space it in relation to said movable die.

15. In a riveting machine, the combination 40 45 of a stationary die, and a movable die,

plungers mounted on either side of said movable die adapted to engage rivet heads in the work being riveted, and means for adjusting the distance between said plungers.

16. In a riveting machine, the combination 50 of a stationary die, and a movable die, a plunger mounted adjacent said stationary die adapted to engage the head on one end of a rivet in the work being riveted, and a plunger mounted adjacent said movable die 55 adapted to engage the head on the other end of said rivet, whereby the work is steadied and properly spaced between the dies.

17. In a riveting machine, the combination 60 of a stationary die, and a movable die, 65 a plunger mounted adjacent said stationary die adapted to engage the head on one end of a rivet in the work being riveted, a plunger mounted adjacent said movable die adapted to engage the head on the other end of said rivet, and means whereby said plunger adjacent the movable die moves forward to engage its rivet head and carries the work forward, so that the head on the other end of the rivet is engaged by the plunger 70 mounted adjacent the stationary die.

18. In a riveting machine, the combination 75 of a stationary die, and a movable die, plungers mounted adjacent said stationary die adapted to engage the heads on rivets, in the work being riveted, plungers mounted adjacent the movable die adapted to engage the heads on the other ends of said rivets, and means for adjusting said plungers so that they are in proper position to engage 80 said rivet heads.

In testimony whereof we have hereunto signed our names, at Philadelphia, Pennsylvania, this nineteenth day of June, 1916.

FRANCIS P. KENNEY.
